UNITED STATES PATENT OFFICE.

MARSHALL M. WELCH, OF ATLANTA, GEORGIA.

ELECTRICAL CIRCUIT-CLOSER.

SPECIFICATION forming part of Letters Patent No. 375,238, dated December 20, 1887.

Application filed September 14, 1887. Serial No. 249,682. (No model.)

To all whom it may concern:

Be it known that I, MARSHALL M. WELCH, a citizen of the United States, residing at Atlanta, in the county of Fulton and State of Georgia, have invented certain new and useful Improvements in Electrical Circuit-Closers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to improvements in circuit-closers, especially designed for use in signaling on railway-trains, the object being to produce an instrument certain in its action that may be readily attached to the car and will at all times have its contact points protected from dust or other matters liable to prevent their perfect action as conductors.

20 In carrying out my invention as applied to railway-cars I provide a suitable piece of varnished wood or other poor conducting material to act as a support for the operative parts of apparatus. This support is secured to the end of a car over the ordinary opening for the passage of the bell-cord, and is pierced with 25 a similar opening registering with that in the car. Attached to this support are two metallic springs placed diametrically opposite each other, one on each side of the orifice through said support, and connected with each 30 of these springs, preferably by the screws which hold them in place, is an insulated wire, which wires may be brought together at a short distance from the point at which they are attached and slightly twisted together, so as to 35 form but a single cord or a double conductor tinsel-cord with the ends so separated as to be applied, as above described, to the end of which is attached a suitable coupler, by means of which it may be connected with a 40 similar device upon the next car. The inner ends of the springs are turned outward, and each carries a contact-point, to which is secured, by suitable set-screws, an insulated wire. These wires are brought together and slightly 45 twisted, so as to form a cord which is passed through the central opening and connected with a similar apparatus on the opposite end 50

of the car. These springs keep the contact-points normally a short distance apart; but the arrangement of parts is such that a pull 55 upon the wires or double-conductor tinsel-cord as they pass through the car brings these points together, thus closing the circuit and allowing the passage of electricity through the insulated wires. To protect the contact-points 60 from dust I inclose them within a light hood or tube of rubber, which fully protects them and at the same time offers little resistance to their movements.

In the accompanying drawings, illustrating 65 this invention, Figure 1 is a sectional view of the ends of two adjoining cars provided with my improved circuit-closer, with the wires or double tinsel-cord between the cars connected by a suitable coupling. Fig. 2 is a side elevation of the circuit-closer, illustrating the general arrangement of the several parts. Fig. 3 is a longitudinal section through the contact-points and their supports. Fig. 4 is a perspective view of the covering-hood which protects the contact-points. 75

In the figures, A represents the end of a car, and B the supporting-piece, of a suitable non-conducting material, to which the other parts of the apparatus are connected. Through the 80 middle of this piece B is formed an orifice, which, when the apparatus is in use upon a car, registers with the bell-cord orifice a' in the end of the same.

Secured to the piece B, on opposite sides of 85 the opening a, by means of screws b and b', are the two curved metallic plate-springs C C'. Each of these springs carries at its outer end, and firmly secured thereto, a contact point or block, as D and D'. The point D, secured to 90 the spring C, has its inner end excavated to form a conical recess fitted to receive the coned end of the point D' when they are brought together. Diametrically through each of these points D and D' is bored a hole, c, 95 through which passes one branch of the insulated double-wire cord or double-conductor tinsel-cord E, and in which hole said branch is secured by a set-screw, d. As hereinbefore stated, the normal position of these contact-points is a short distance apart, in which position they are retained by the elasticity of the curved springs; but when it is desired to bring them together a pull upon the cord E will 100

cause both points to swing inward toward each other, the springs acting like pivoted arms to allow such a movement, and when in contact they will be thus retained so long as 5 the tension upon the cord E is maintained. The connection is continued through adjacent cars by the branches of the insulated cord F, which are connected to the springs C and C' by means of the screws b, which screws may 10 fulfill the double purpose of securing the wires to the springs and the springs in place. For the purpose of protecting the contact-points from dust I encircle each one near its inner end with a groove, e. These grooves 15 receive the corded ends of the hollow soft-rubber bulb or hood G, which completely incloses the ends of the points and the space between them. The peculiar form and material of this hood allows it to conform readily to the dif- 20 ferent positions of the points without resisting their movement or releasing the hold of said hood in the grooves, while it forms a perfect protection to the contact-points against the gathering of dust or other matters upon them 25 which might injure their electrical conductivity.

Having thus described my invention, I claim as new, and desire to secure by Letters Patent of the United States, the following:

1. In a circuit-closer, the two contact-points 30 mounted upon curved springs by which they are held normally out of contact, and each connected with one branch of a double insulated wire cord, said cord being arranged and adapted to bring the points in contact when 35 pulled, substantially as specified.

2. In a circuit-closer, the curved spring supported upon a bed having a central orifice, in combination with the contact-points, one of which is recessed at the end, the other coned 40 to fit said recess, and the double insulated wire cord passing through said orifice in the bed and adapted to bring the points in contact, as set forth.

3. As an improvement in electrical circuit- 45 closers, the combination of the centrally-perforated support, curved spring secured thereto, contact-points carried by said springs, and protecting-hood arranged to cover and protect said points, as set forth.

In testimony whereof I affix my signature in presence of two witnesses.

MARSHALL M. WELCH.
